SHIELD FOR ELECTRIC PLUGS

John W. Brown, South Euclid, Ohio, assignor to
Dancyger Manufacturing Company, a corpora-
tion of Ohio

Application May 1, 1947, Serial No. 745,272

2 Claims. (Cl. 206—46)

1
This invention relates to shields and more particularly to shields for the prongs of the plugs for electrical merchandise, such, for example, as lamps, household appliances and other devices.

In the packaging and wrapping of electrical merchandise, not infrequently the prongs of the electric plug scratches, mars or otherwise damages the finish of the merchandise which destroys the true value thereof.

An object of this invention is the provision of a shield for the prongs of an electric plug for electrical merchandise such that the shield will prevent the prongs of the plug from contacting the surface of the merchandise whereby the merchandise is protected against scratching, marring or otherwise being damaged.

Another object of this invention is the provision of a shield for the prongs of an electric plug which may be economically manufactured and which may be readily attached to the electric plug for shielding the prongs thereof.

Another object of this invention is the provision of a shield for the prongs of an electric plug whereby the shield is anchored to at least one of the prongs of the plug for holding the shield thereto.

Another object of this invention is the provision of a shield for the prongs of an electric plug which comprises a hood portion for shielding the prongs and which comprises end portions which may be anchored to at least one of the prongs and the electric cord which leads to the plug.

Other objects and a fuller understanding of the invention may be had by referring to the following description and claims taken in conjunction with the accompanying drawing, in which:

Figure 1 is a plan view of a strip of material which may be attached to the electric plug to constitute a shield for the prongs thereof;

Figure 2 is a side view of the shield shown as being mounted on the electric plug;

Figure 3 is a view of Figure 2 looking from right to left of the Figure 2;

Figure 4 is a modified form of the strip shown in Figure 1;

Figure 5 is a side view of the strip as shown in Figure 4 and mounted upon the electric plug; and

Figure 6 is a side view of Figure 5 looking from right to left of the Figure 5;

With reference to Figures 1, 2 and 3, the shield is constructed from a strip of material 20 having two end portions 21 and 22 and an intermediate loop portion 23. The strip 20 may be made from any suitable material, such, for example, as paper, cardboard, plastic, or any other bendable or

formable material which may be looped about the prongs for shielding same and which may be suitably attached to the electric plug. In Figure 2 the loop portion 23 is further sub-divided into a top 24, a short side 25 and a long side 26. The end portion 21 is provided with two spaced slot openings 27 which are adapted to slide over the prongs 30 of the electric plug 31. The end portion 22 is provided with an aperture 28 and a slot 29 which extends from the end of the strip at an angle to the aperture 28. In mounting the strip of material 20 to the electric plug 31, the operator first inserts the prongs 30 through the two slot openings 27 and forces the end portion 21 down flat against the flat portion of the plug 31 from which the prongs 30 extend. The loop portion 23 is then looped about the prongs with the short side 25 extending upwardly substantially parallel to the prongs of the plug, with the top 24 extending substantially horizontally over the prongs and with the long side 26 extending downwardly on the opposite side of the plug. The end portion 22 is then bent inwardly towards the electric cord 32 of the plug and the slot 29 is spread open to permit the electric cord 32 to slide therethrough and into the aperture 28, which anchors the end portion 22 to the electric cord. The loop portion 23 which comprises the short side 25, the top 24 and the long side 26, constitutes a hood for the prongs and prevents the prongs from contacting or striking the finished surface of the electrical merchandise to which the electric plug and cord is attached. The outside surface of the shield and particularly the long side 26 may be provided with indicia, such, for example, as advertising matter, trade marks, or other information for the benefit of the user.

In Figure 4 there is shown a modified strip 36 in that the end portion 21 is provided with a single slotted opening 37 which is adapted to be inserted over one of the prongs of the electric cord, see Figures 5 and 6. In the modified form of Figure 4, the strip is looped around the prongs in the same manner as that previously described except that the shield is looped around the plug at right angles to that shown in Figures 2 and 3. In Figure 4, however, the end portion 21 may be provided with two spaced slots 37 instead of one in which event the two prongs 30 would extend through the two slots and the end portion 21 would extend all the way across the surface of the plug from which the prongs extend.

In all the forms of my invention the strip of material is looped about the prongs to constitute

3

a hood to shield the prongs from striking or otherwise damaging the surface of the electrical merchandise to which the plug is attached.

What is claimed is:

1. A shield for the prongs of an electric plug having an electric cord entering the plug for connection to said prongs, said shield comprising a strip of material having first and second end portions and a loop portion intermediate said end portions, said first end portion having spaced openings through which said prongs may be inserted to anchor said first end portion to said prongs, said loop portion extending around said prongs and constituting a hood for shielding said prongs, and means for attaching said second end portion to said electric cord.

2. A shield for the two spaced prongs of an electric plug having an electric cord entering the plug for connection to said prongs, said shield comprising a strip of material having first and

second end portions and a loop portion intermediate said end portions, said first end portion having an opening through which at least one of said prongs may be inserted to anchor said first end portion to said prong, said loop portion extending around said prongs and constituting a hood for shielding said prongs, and means for attaching said second end portion to said electric cord.
